US0D1107190S

(12) **United States Design Patent** (10) **Patent No.:** **US D1,107,190 S**
(45) **Date of Patent:** **** Dec. 23, 2025**

(54) **SINK STRAINER**

(71) Applicant: **Hongmin Liu**, Fujian (CN)

(72) Inventor: **Hongmin Liu**, Fujian (CN)

(**) Term: **15 Years**

(21) Appl. No.: **29/955,431**

(22) Filed: **Aug. 1, 2024**

(30) **Foreign Application Priority Data**

Apr. 25, 2024 (CN) 202430239826.8

(51) **LOC (15) Cl.** **23-01**

(52) **U.S. Cl.**

USPC **D23/261**

(58) **Field of Classification Search**

USPC D23/259-261, 268

CPC .. A47K 1/14; E03C 1/264; E03C 1/26; E03C

1/262

(57) **CLAIM**

The ornamental design for a sink strainer, as shown and described.

DESCRIPTION

FIG. 1 is a top perspective view of a sink strainer, showing my new design.

FIG. 2 is a bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

1 Claim, 8 Drawing Sheets
